INVENTOR

Eben F. Oliver

Walter Beekman
ATTORNEY

UNITED STATES PATENT OFFICE.

EBEN F. OLIVER, OF JERSEY CITY, NEW JERSEY, ASSIGNOR TO KORRECTOLITE COMPANY, INC., OF NEW YORK, N. Y., A CORPORATION OF NEW YORK.

SHADE-SUPPORTING MEANS.

Application filed November 23, 1922. Serial No. 602,723.

To all whom it may concern:

Be it known that I, EBEN F. OLIVER, a citizen of the United States, and a resident of Jersey City, in the county of Hudson and State of New Jersey, have invented certain new and useful Improvements in Shade-Supporting Means, of which the following is a specification.

This invention relates to a shade supporting means for electric bulbs and has for its main object and feature the production of simple and inexpensive means for rigidly and detachably securing a shade to an electric bulb.

15 In the accompanying drawings the invention is disclosed in a concrete and preferred form in which:

Fig. 1 is a vertical sectional view through a shade or bowl showing the bulb in elevation and disclosing the carrying means for the shade.

Fig. 2 is an enlarged vertical sectional view on a plane at right angles to the section of Fig. 1.

25 Fig. 3 is a detail view of a spring clip.

Fig. 4 is a vertical sectional view of a carrying member.

Fig. 5 is a sectional view on the plane of line 5—5 of Fig. 2.

30 Fig. 6 is a sectional view of the lower end of Fig. 2 and on a plane at right angles thereto.

1 indicates an electric bulb and 2 is the shade or bowl to be supported on the bulb.

35 3 is a spring clip having two main loops 4 and a downwardly projecting loop 5. The main loops pass around the bulb as shown so that loop 5 projects downwardly from the tip end of the bulb and forms a yoke.

40 6 is a carrying member in the form of a cylinder having vertical slots 7. The upper end of 6 is in effect an abutment portion in that, when loop 5 is slipped over 6, the wires constituting loop 5 extend through

45 slots 7 and at the point 8 where loop 5 begins the wires thereof engage the end 9 of slots 7 and thus draw carrying member 6 against the tip of the bulb. 10 indicates a cushioning member seated in the abutment

portion of member 6 and into which the tip 50 of the bulb projects. The lower end of member 6 is threaded and the shade is provided with a central opening somewhat larger than member 6. 11 is a nut having internal threads which engage the threaded 55 portion of carrying members 6 and thus draws the shade against the clip at the point 8. 12 indicates washers that may be interposed to protect the glass of the shade.

It will of course be understood that the 60 word "downwardly" is used in a relative sense, and that the bulb may extend in any direction.

I claim:

1. The combination with an electric bulb, 65 of a spring clip to clasp the bulb, a downwardly projecting loop on said spring clip forming a yoke extending below the tip of the bulb, a carrying member having an abutment portion abutting against the tip 70 of the bulb and having vertical slots in its side wall below the abutment portion, said loop passing outside the abutment portion and into the slots aforesaid to draw the carrying member against the bulb, a shade 75 having a central opening through which the carrying member passes, and means for securing the shade to the carrying member.

2. The combination with an electric bulb, 80 of a spring clip to clasp the bulb, a downwardly projecting loop on said spring clip forming a yoke extending below the tip of the bulb, a carrying member having an abutment portion abutting against the tip 85 of the bulb and having vertical slots in its side wall below the abutment portion, said loop passing outside the abutment portion and into the slots aforesaid to draw the carrying member against the bulb, a shade having a central opening through which the carrying member passes and a threaded nut 90 engaging the carrying member to draw the shade against the spring clip.

Signed at New York, in the county of New York and State of New York, this 95 21st day of November, 1922.

EBEN F. OLIVER.
